UNITED STATES PATENT OFFICE.

JOSEPH H. LYNCH, OF ASBURY PARK, NEW JERSEY.

SAFETY-PIN.

1,369,822.

Specification of Letters Patent.

Patented Mar. 1, 1921.

Application filed April 23, 1919. Serial No. 292,064.

To all whom it may concern:

Be it known that I, JOSEPH H. LYNCH, a citizen of the United States, residing in Asbury Park, in the county of Monmouth and State of New Jersey, have invented certain new and useful Improvements in Safety-Pins, of which the following is a full and clear specification.

The present invention relates to safety pins; and particularly to safety pins such as are adapted for use in laundries and such, where the pins with suitable identification marks thereon are attached to the different articles to be laundried before they pass through the laundrying process, so that after they have been laundried, they may readily be identified. It will thus be seen that for this purpose, it is very desirable to have a pin which will not readily become unfastened or opened, and which at the same time is strong and durable enough to withstand the crushing force to which it is often subjected by the machinery usually used in the laundries. The object of the present invention is to provide such a pin, and other and further objects will appear in the specification and be pointed out in the annexed claims.

In the accompanying drawings, which illustrate my invention,

Figure 1 is a view of what I will call the bottom of the safety pin, showing the slideable member in locking position;

Fig. 2 is a similar view showing the slideable member in open position;

Fig. 3 is a view of the top of the pin, showing the slideable member in locking position;

Fig. 4 is a top perspective view of the pin with the slideable member removed, and

Fig. 5 is a perspective view of the slideable locking member.

Referring more specifically to said drawings, 1 indicates a shield formed in any suitable manner from a flexible material such as sheet metal, and having the extended portion 2 upon which may be placed numbers, letters, or any other desired marks. The sides of the shield are bent over as indicated at 3 and 4; the bent portion 3 embracing and being secured to the one end of the pin member 5, while the bent portion 4 serves as a keeper for the other relatively movable end of the pin member 5. The portion 7 is turned down in order to brace the bent portion or keeper 4; and for the sake of

uniformity the portion 6 is also bent down. A slot 8 is provided in the shield 1, in which the slideable locking or obstructing member 9 is disposed. The transversely extending upper surface 9^a of this member 9 is of sufficient length to extend substantially from the inner edge of bent over portion 3 to the inner edge of bent over portion 4, and thus when in the position shown in Fig. 3 it locks the relatively movable end of pin member 5 against displacement from keeper 4. However, when the slideable member 9 is moved to the open position shown in Fig. 2, the pin member may readily be removed from keeper 4.

In order to prevent the accidental displacement of member 9 from open or closed position, the slot 8 is made relatively narrow at its intermediate portion, as shown; and the member 9 is so proportioned that in order for it to pass by the intermediate portion of the slot, it has to be compressed. The resistance thus offered to its passage tends to prevent its accidental displacement. When at either end the member expands to normal.

The height of member 9 preferably is such that when it is in the slot 8 the top surface 9^a is substantially in alignment with the top surface of bent over portions 3 and 4; in order that any pressure on the top of the shield may be taken up evenly by the bent over portions and the slideable member. Furthermore, this construction has the advantage that it gives a smooth and uniform upper surface to the pin so that the slideable member is unlikely to "catch" on and become unlocked by articles with which it comes in contact.

The sides of this member 9 are also preferably curved inwardly as at 9^b so that any pressure on the top of the pin which is exerted on said member will tend to compress the member vertically without causing it to expand laterally; hence it will remain in its original position with relation to bent over portion 4, since the latter will also be compressed, and it will therefore not become inoperative.

I claim:

1. A safety pin comprising a pin member, a shield having one side rigidly secured to one end of said pin member and the other side forming a keeper adapted to receive the other end of said pin member, said shield being provided with a slot, a slideable member disposed in said slot adapted to lock the

end of said pin member in said keeper, said slideable member being movable into and out of locking position, and means adapted to offer resistance to the movement of said slideable member into and out of locking position.

2. A safety pin comprising a pin member, a shield having one side rigidly secured to one end of said pin member and the other side forming a keeper adapted to receive the other end of said pin member, said shield being provided with a slot relatively narrow at its intermediate portion, and a slideable member disposed in said slot adapted 15 to lock the end of said pin member in said keeper, said slideable member being movable into and out of locking position and adapted to be compressed by the walls of said slot during such movements.

20 3. A safety pin comprising a pin member, a shield of flexible material having opposite sides bent over, one bent portion embracing and secured to one end of said pin member and the other bent portion forming a keeper

for the other end of said pin member, and a 25 separate locking member secured to said shield and movable thereon into a position substantially closing a portion of the pin receiving portion of said keeper, said locking member having its upper surface substantially in alinement with the upper surface of the bent-over portions of the shield.

30 4. A safety pin according to claim 3 in which the sides of the locking member are curved inwardly.

35 5. A safety pin comprising a pin member, a shield having one side rigidly secured to one end of said pin member and the other side forming a keeper adapted to receive the other end of said pin member, a compressible locking member associated with said shield and adapted to lock the end of said pin member in said keeper, said locking member being movable into and out of locking 40 position, and means for compressing 45 said locking member during such movements.

JOSEPH H. LYNCH.
